Inventor:

UNITED STATES PATENT OFFICE.

HENRY A. MATTHEWS, OF WATERBURY, CONNECTICUT.

STOVE DRUM OR CYLINDER.

SPECIFICATION forming part of Letters Patent No. 269,437, dated December 19, 1882.

Application filed May 31, 1882. (No model.)

To all whom it may concern:

Be it known that I, HENRY A. MATTHEWS, of Waterbury, in the county of New Haven and State of Connecticut, have invented a new and useful Improvement in Stove-Drums; and I do hereby declare the following, when taken in connection with the drawings and the letters of reference marked thereon, to be a full, clear, and exact description of the same, and which said drawings constitute part of this specification.

Figure 1 is a perspective view.

My invention has for its object a stove-drum which shall be light, ornamental, cheap, and not liable to rust. The drum in a heating-stove ordinarily incloses and contains that part of the stoves which constitutes the coal-reservoir in base-burning stoves and the upper part of the combustion-chamber in other stoves. The drum is a part of the stove exposed to view, and its beauty as well as its utility are objects desired and sought after. These drums have heretofore been made of cast-iron and of sheet-iron. When made of cast-iron the ornaments are cast upon the plates. When made of sheet-iron the ornaments are riveted upon the drum.

The manner in which I construct my stove-drum is as follows: I take a piece of sheet-brass of the desired size and pass it between embossing-rollers. These rollers leave the surface of the brass embossed with the pattern cut upon the roller. I then round the sheet-brass into the form of a cylinder or drum, with the embossed side outward, and fasten the

ends in any of the ordinary methods, preferably by brazing. 35

I do not claim as my invention making a stove-drum of brass, broadly, when the brass is unornamented. Brass is the only metal of sufficient cheapness which possesses the requisite tenacity and toughness for stove-drums, and at the same time sufficient ductility to enable it to be embossed in the manner I have above described.

The advantages of my improved stove-drum are, first, that the ornaments form a part of the metal drum and cannot fall off; second, that the drum is not perforated with rivet-holes for the purpose of fastening on the ornaments; third, that the ornaments upon my drum are cheaper and of more beauty and finish than the old ornaments; fourth, that it will not rust.

In the drawings, A, Fig. 1, represents the stove. B is my improved drum; C C, the embossed surfaces upon the drum. Fig. 2 shows a portion of the embossed surface of the drum on an enlarged scale.

What I claim as my invention, and desire to secure by Letters Patent, is— 60

As a new article of manufacture, a stove-drum of brass having embossed ornamental surfaces C C integral with said drum, substantially as and for the purpose described.

HENRY A. MATTHEWS.
